(57) **CLAIM**

The ornamental design for a hair brush as shown and described.

DESCRIPTION

FIG. 1 is a first rear perspective view of a hair brush, illustrating our new design;

FIG. 2 is a second rear perspective view thereof;

FIG. 3 is a first front perspective view thereof;

FIG. 4 is a second front perspective view thereof;

FIG. 5 is a front elevation view thereof;

FIG. 6 is a rear elevation view thereof;

FIG. 7 is a top plan view, with a bottom plan view being a mirror image thereof;

FIG. 8 is a left-side elevation view thereof; and,

FIG. 9 is a right-side elevation view thereof.

The broken lines in the figures illustrate portions of the hair brush, and form no part of the claimed design.

1 Claim, 8 Drawing Sheets
